[57] CLAIM

The ornamental design of an automotive vehicle body,
as shown and described.

DESCRIPTION

FIG. 1 is a right side elevational view of an automotive vehicle body showing my new design.

FIG. 2 is a front elevational view thereof.

FIG. 3 is a rear elevational view thereof.

The left side of the vehicle is substantially a mirror image of the right side shown in FIG. 1, while the top of the vehicle is plain and unornamented.

The broken lines in the drawing are for illustrative purposes only.
